UNITED STATES PATENT OFFICE

WILLIAM B. STEVENSON, OF MOORESTOWN, NEW JERSEY, ASSIGNOR TO VICTOR TALK-
ING MACHINE COMPANY, A CORPORATION OF NEW JERSEY

DESIGN FOR A CABINET FOR SOUND PRODUCING AND REPRODUCING INSTRUMENTS

Application filed May 6, 1929. Serial No. 31,106. Term of patent 14 years.

To all whom it may concern:

Be it known that I, WILLIAM B. STEVENSON, a citizen of the United States of America, and a resident of Moorestown, county of Burlington, New Jersey, have invented a new and original Design for Cabinet for Sound Producing and Reproducing Instruments, of which the following is a specification, reference being had to the annexed drawings, forming a part thereof, and which show a cabinet embodying my new design, Fig. 1 showing a

front perspective with the doors in the open position and Fig. 2 a front perspective with the doors in the closed position.

I claim:—

The ornamental design for a cabinet for sound-producing and reproducing instruments as shown.

In testimony whereof I have signed this specification.

WILLIAM B. STEVENSON.
